UNITED STATES PATENT OFFICE

CHARLES L. GOODRUM, OF ATHENS, GEORGIA, ASSIGNOR OF ONE-HALF TO LOUIS G. PACENT, OF NEW YORK, N. Y.

SWITCH CONTROL MECHANISM FOR AUTOMATIC TELEPHONE SYSTEMS

Application filed March 31, 1932. Serial No. 602,189.

My present invention has for its object the provision of a switch control and operating mechanism for automatic telephone systems which is capable of operation on low-line voltages such as 22½ volts as compared with the 48 volts now used, and one which is less affected by line losses of current usually encountered in practice.

A further object of my invention is to supply a circuit arrangement which permits greater tolerance in the operating characteristics of the various sets of contacts which are called into play in controlling the operation of a switch. By means of my invention the present-day practices of establishing a very careful proportioning of the time-of-dwell or holding of the making contacts, which close an operating circuit with reference to the period in which a cooperating set of breaking contacts are opened, is avoided. This is a feature which lessens the original cost of assembly of the apparatus and the installation of the system and materially reduces the subsequent cost in the maintenance of the telephone lines. Further, my invention provides a switch mechanism which is less dependent than the present systems upon accuracy in the regularity with which the operating impulses are transmitted by the subscriber's dialing device.

To these and other ends my invention consists in further improvements, all as will be fully described in the following specification, the novel features being pointed out in the appended claims.

Fig. 1 is a diagrammatic illustration of a switch showing the manner in which a connection is established between two subscribers' stations and the means employed for effecting the step-by-step movement of the switch wipers and their release upon the termination of a call;

Fig. 2 is a view showing the essential mechanical elements of a switch mechanism;

Fig. 3 is a sectional view thereof taken on line 3x—3x of Fig. 2;

Fig. 4 is a diagrammatic view of a subscriber's impulse transmitter, and

Figs. 5 and 6 are schematic illustrations of

certain modifications of the circuit layout of Fig. 1.

Similar reference characters in the several figures indicate similar parts.

It is well recognized in engineering practice employed in the manufacture, installation and maintenance of the present two-wire automatic telephone systems that certain standards in line voltages and relative timing adjustments of certain contacts controlling the operating circuits must be maintained in order that unfailing accuracy in the stepping movement of a switch or a series of switches employed for establishing the connection of a calling party's line with a desired called-party's line may be effected. In the operation of the present-day systems, in which the switches are controlled over the two wires comprising the subscriber's telephone line, certain switch-control circuits are established at the central office by means of a so-called impulse relay comprising an armature which vibrates in response to interruptions created on a telephone line by the subscriber's dialing equipment. In its normal or released position this armature engages a contact closing a circuit through the motor magnet of the switch and when said armature is attracted it engages a forward contact to close a circuit through an associate slow-to-release relay. The latter is energized upon the closing of the subscriber's line and is maintained energized during the transmission of current impulses to maintain the continuity of the motor magnet circuit until after the completion of the dialing operation.

In order to insure the positive operation of the contacts on the quick and slow relays just mentioned particularly, and to an equal extent insure the proper operation of the release and switch stepping magnets, it has been deemed essential to use a comparatively high line voltage—a voltage which is far greater than that required for communication purposes on the telephone lines. In addition to this, it has been found necessary to construct the subscriber's dialing device or impulse transmitting mechanism to operate within very accurate limits so that practically no variation in their operation is al-

lowed over a group of impulses. In order to insure the transmission of the required voltage to the motor magnet circuit and the associate slow control relay a very careful 5 timing of the armature of the quick operating or pulse relay is required. It will be sufficient for illustrative purposes in this case to state that the duration of the time in which the armature is allowed to remain attracted in the make position (during which the telephone line is closed by the dialing device contacts) is one-third of the unit time, and the period in which said armature is allowed to rest in engagement with its back 10 contact (the line circuit being then open at the dialing contacts) is the remaining two-thirds of this unit. Great accuracy in timing the driving mechanism by which the dialing contacts are opened and closed must also 15 be maintained so that in the transmission of the entire series of ten digits the variation in successive operations shall not be more than one-tenth of a second. The reason for the allowance of the greater portion of the 20 unit time when the dialing contacts are closed and the armature of the control relay is attracted is to allow for the movement of the armature and then permit current saturation of the associate slow relay and motor magnet 25 to be accomplished.

In order to obviate many of the difficulties resulting from the limitations imposed by reason of these adjustments and current requirements, I have devised certain improvements which will become apparent from a 30 description of my new system as a whole.

To facilitate the description of my improved circuits I will first refer to certain details of a switch mechanism suitable for 35 use in connection with them. In Figs. 2 and 3 I have shown schematically certain necessarily associate parts of a switch construction comprising an arcuate terminal bank in which insulated terminals are arranged in 40 vertical sets such as indicated by 1, 2 and 3 (Fig. 3) the first two comprising terminals for an incoming subscriber's line wires and the third being for a busy test circuit for such line. In practice it will be understood that 45 where the system is extended to a point where more than one switch is required for interconnecting a large group of subscribers' lines, additional switches are provided and these terminals are connected in multiple or 50 the switches are otherwise disposed to provide for the required classification of service. Rotatably mounted in front of the terminal bank are the cooperating switch wipers 1a, 55 2a and 3a carried on a journal 4 to which is 60 fixed a ratchet wheel 5. Spring fingers 1b, 2b and 3b extending inwardly from a support 65 engage the hubs of the wipers. A coil spring 7 of the required tension is connected to the journal 4 and its supporting frame 65 serves to restore the switch wipers to their

normal position when they are released as indicated in Fig. 2. The switch is further provided with sets of off-normal contact springs 8, 9 and 10 which are arranged above and at one side of the ratchet wheel 5 on a support or bracket 11. The uppermost spring has an extension or finger 12, projecting into the path of a pin 5a which when the switch is advanced releases these sets of contacts. When the switch is in its normal position springs 8 and 9 are closed against their cooperating contacts 8a and 9a and spring 10 is disengaged from its contact 10a. The circuit condition controlled by each of these several contacts is reversed as soon as the switch is advanced one step.

In Fig. 4 I have shown diagrammatically the subscriber's dialing device or transmitter. The latter comprises a rotatable member 13 adapted to be driven in one direction by the tension of a spring 14. An oscillatory setting member in the form of a ratchet wheel 13a is directly connected to the spring and when it is restored to its original position causes the actuator 13 to be driven through the pawl 13b. The dialing device also embodies a pair of contacts through which the telephone line is normally closed and comprising a spring 18 supported in a holder 19, and carrying on its lower side a stud 18b which when acted upon by the member 13 will disengage the contact 18a.

The subscriber's line A, B when in use extends through the normally closed contacts 18, 18a as shown in Fig. 1 and includes the subscriber's telephone apparatus comprising the transmitter T, receiver R and the usual switch hook contacts H.

The subscriber's circuit extends through relay contacts to be further described and terminates in the switch wipers 1a and 2a. In order that this line may be called by other subscribers, terminals are allocated to it on the switch bank. For the purposes of description I have also illustrated in Fig. 1 a called party's line A² and B² which represents one of several which terminate on different sets of switch terminals 1, 2 and 3. If the system requires two or more switches (a second switch being indicated at E) the corresponding terminals of the various lines are connected in multiple as will be understood.

In a telephone system designed to accommodate a considerable number of subscribers, it is desirable to use a proportional number of switches which are very much less in number than are the lines which are served, and to provide for the automatic selection of one of the group of lines on which a call may be initiated. This is accomplished by a finder switch the function of which is to connect the calling line to an idle trunk leading to a connector switch over which the desired connection can be effected by the transmission of the required number of impulses rep-

resenting digits to advance its wipers into engagement with the terminals of the called party's line. To this end the line wires from the subscriber's station A appear as terminals A³ B³ of a line finder switch F to which the conductor A and B are joined by wires A⁴ and B⁴. The wipers f' and f² of the finder's switch are terminals of a trunk, comprising the conductors A⁵, B⁵, leading to the connector switch control mechanism at which point they lead through the main control relay A' and its associate control relay C. The effect of the operation of the line finder switch F is to extend the calling line and to place the control relays of the connector switch in direct connection with the two sides of the subscriber's circuit and also to extend said circuit beyond this point, by conductors A⁶, B⁶, through relays which are actuated when the called party answers so that a talking connection is established between the calling and called party's stations through the advanced position of the connector switch wipers.

The function of the dialing contacts of the impulse transmitter is to provide means for intermittently opening the circuit of the subscriber's line conductors in one of which I provide a main relay A' and in the other an associate control relay C. The former is in circuit with battery X which is the usual central office storage battery having a grounded connection w' leading from its positive pole and the latter relay is connected to the opposite or grounded pole of the battery as indicated at c'. A common battery is employed for supplying all of the circuits which are referred to herein but in order to simplify the illustration separate batteries are shown with appropriate ground connections which indicate a common return for the several circuits.

The main and associate central relays may be of a similar construction but as the main control relay is on the wet or battery side of the line it will when energized operate to close a pair of contacts a² and the associate control relay on the dry side of the line, serves to open a pair of contacts c². The contacts a² apply a grounded connection a³ through conductor 20 the coil of a slow to release relay D to battery X⁰ and its ground. On this relay are a pair of normally open contacts d one of which is grounded at d' and the other being joined to the armature of the pair of contacts c² by wire 20^a. Relay D is rendered sluggish in the release of its contacts d by providing its core with a jacket of copper or other non-magnetic metal the purpose being to enable it to maintain its contacts d closed during the vibrations of the armature of the pairs of contacts a² and c². The contacts c² control the stepping movement of the motor magnet of the switch in response to impulses transmitted by the action of the subscriber's dialing device and their operation must be positive. There is no requirement for the contacts a² to vibrate but as the circuit through relay A' is opened simultaneously with that of relay C, I reduce the spring tension on the armature of contacts a² to such a weak point of adjustment that when a series of impulses traverse the subscriber's circuit it will either hold over in its attracted position or possibly flutter only slightly without opening the circuit for a sufficient length of time to rob the slow relay of current. This adjustment is such that at no time during the transmission of a series of impulses will said armature a² break the energizing circuit of relay D for a length of time sufficient to allow it to become demagnetized. This is considered an important feature as the contacts a² are making, or normally open contacts, while those of contacts c² are breaking, or normally closed contacts, and by placing them upon separate relays of similar electrical characteristics a balance on the two sides of the line can be maintained and there is no need of considering any differential operation or relative timing of the movement of the armatures of said pairs of contacts. Thus it will be seen that I am able to avoid the first cost incurred in building a dialing device which controls accurately within close limits the open and closed periods on the subscriber's line and to greatly reduce the second cost involved in the maintenance of these dialing devices and the central office apparatus in service. It will also be appreciated that in avoiding the necessity of accurately timing the relative movement of the contacts on the two control relays their operation will not be so greatly affected by losses in current due to leakage from one or the other of the line conductors due to the more common causes experienced in telephone exchange operations.

For advancing the switch I employ a motor magnet M having an armature m which is attracted against the tension of a spring m' and carries a pawl or finger m² which engages with the teeth of the ratchet wheel 5 to advance the switch wipers one step upon each impulse of current transmitted to the magnet.

In order to lock the switch in its operated position, and subsequently permit it to be restored to its normal position, I arrange the release magnet L and its circuit in such a manner that it is capable of performing both of these functions. The release magnet has a pivoted armature l carrying a detent or dog l' which is normally held out of engagement with the ratchet wheel 5 when in the retracted position by a pin l². Upon the attraction of the armature of this magnet the pawl is relieved and allowed to move upwardly under the influence of a spring l³. The relay magnet L is connected at one terminal

to battery X' and at its opposite extremity to the conductor 21 leading to contact $8a$ of the off-normal spring 8. From spring 8 a conductor 22 leads to conductor 20^a . Hence it 5 will be seen that when the main control relay A' and the slow relay D which it controls is initially energized by closure of the subscriber's line the magnet L is energized so that the pawl l' engages the first ratchet 10 tooth and as the ratchet wheel 5 is subsequently advanced it will be held in the operated position. In order to hold magnet L energized after the off-normal contacts 8 and $8a$ are broken a branch circuit is provided, as 15 indicated by the wires 23 and 24 which extend to a pair of contacts L' which are closed upon the energization of magnet L and thereafter serve to bridge the first mentioned contacts 8 and $8a$ in this circuit. In practice I 20 prefer to make the release magnet slow to de-energize (in the manner described with reference to the relay O) as this contributes somewhat to the assembly, testing and maintenance of the apparatus but it will however 25 be understood that this magnet need not be retarded in its action.

The motor magnet is intermittently energized by the closing of the contacts c^2 on the associate control relay C, but as this relay 30 remains energized over the closed subscriber's circuit after the transmission of the last impulse from the dialing device, it is necessary to provide in the circuit of the motor magnet means for maintaining its continuity 35 during the period the impulses are being transmitted, said means being so arranged that it is actuated upon the first impulse transmitter and disconnected automatically upon the completion of the group of impulses. To this end I provide in the motor 40 magnet circuit a separate control relay O. This is a slow to release relay, the core of which is provided with a copper sheath or equipped with a copper slug which will serve 45 to retain the magnetism therein and delay the opening of its contacts after the circuit of the relay is opened. One terminal of this relay is connected by conductor 25 to the off-normal contact 9^a from which a circuit extends through spring 9 by way of wire 26 50 to the back terminal of the impulse contacts c^2 . The other terminal or relay O is connected by conductor 27 to motor magnet M which receives current impulses from battery X^2 . A pair of contacts o' on relay O are 55 closed when this relay is energized and after the first step of the switch bridge the opening in the circuit created by the opening of the off-normal contacts 9 and 9^a . Consequently, upon each closure of the associate 60 control relay contacts c^2 an impulse of current traverses the motor magnet M and its associate relay O through the bridging contacts o' . The impeded movement, or sluggish 65 release operation of the relay O causes

it to hold over during the rapid vibration of contacts c^2 and it only releases its sustaining circuit contacts o' when the contacts c^2 are open permanently.

In order that the calling subscriber's line 70 may be rendered busy and access thereto prevented after a subscriber has set up a connection with a desired called party, I provide means for grounding the third or associate line terminal 3 of the switch through the 75 closed terminals d of the slow relay D. This busy circuit is rendered operative upon the cessation of movement of the motor magnet by providing on the motor control relay O a pair of contacts o^2 which are held open 80 while this relay is energized and when released serve to extend the circuit through the then closed pair of off-normal contacts 10 and 10^a . The latter is connected by conductor 28 to the back contact of the pair of contacts o^2 , the armature of which is connected by wire 29 to conductor 24 grounded at d' . Leading from spring 10 is a conductor 30 connected to back contact 31 which is engaged by an armature 32 from which extends 85 conductor 33 terminating in the switch wiper 3^a . When the switch is in its normal position contacts 10 and 10^a are open so that subscriber's line A, B is free for selection by any other calling party, but after this line 90 has completed a call a grounded condition of switch wiper 3^a is effected so that an attempted selection of the corresponding set of terminals on which the connector wipers rest will cause the calling party to receive the busy 95 test signal and also render it impossible for him to connect with the busy line.

Upon each impulse to the motor magnet there is closed simultaneously with the movement of its armature a pair of contacts m^3 , 100 the armature of which is connected to ground as indicated at m^4 , its forward contact being joined by the conductor 35 to one winding of the busy test relay P which is fed by battery X^3 the function of said relay is to prevent the passing of ringing current as the switch wipers step over successive sets of line terminals. There are two windings on the busy test relay indicated by p and p' both of 105 which are connected to the battery X^3 , and additional contacts p^2 and p^3 , the latter co-operating with the armature 32 and serving to keep relay P energized when the switch wiper 3^a is advanced into engagement with a 110 grounded or busy terminal of a called line. 115

The ringing current for signaling the called party's line is controlled by the ringing relay Q supplied with current from the battery X^4 and its circuit terminates in the back contact q of armature q' which in its 120 forward movement engages the forward contact p^2 of the busy test relay P. The ringing current apparatus may be an alternating current ringing machine N and a source of direct current N' the circuit for which termi- 125 130

nates in armatures q^2 q^3 on the relay Q. When the latter is energized said armatures engage with forward contacts which in turn are connected to the called party's line by 5 the conductors 36 and 37. A transformer N² has its two windings included in the A. C. and D. C. circuits just mentioned so that the A. C. ringing current is dispatched when the armatures q^2 , q^3 are attracted. In order that 10 this ringing current may be applied intermittently there is placed in the A. C. circuit a commutator n'.

Before tracing this ringing circuit reference should be made to additional instrumentalities by which the calling party's circuit is cut through in such a way that when 15 the called party answers the ringing interruptions are automatically discontinued. The cut through relay S is supplied with 20 current from a battery X⁵ through the resistance s and by means of the conductor 38 (which is a continuation of conductor 30, the completed circuit may be traced to the ground d' through the closed slow to release 25 relay contacts d. However, in order to prevent this circuit from causing the magnet to be energized before the called party answers said relay is short circuited through one of its own contacts and a pair of contacts on 30 the ringing trip relay T. The cut through relay S is provided with an armature s' connected to the switch wiper 1^a by wire 39 and a similar armature s² connected to wiper 2^a by wire 40. Armature s' normally engages 35 its back contact s³ connected by a wire 41 with one terminal of the winding of the trip relay T, the opposite extremity of which is connected to one of the ringing conductors 37. The second armature s² normally 40 engages the back contact s⁴ which is the terminal of the other ringing conductor 36. A third armature s⁵ is mounted on the relay S engaging a back contact s⁶ which is also connected to the conductor 38. On the relay 45 T is an armature t engaging the back contact t'. The armature t is connected by the conductor 43 to battery X⁵ through resistance s and the armature s⁵ and back contact t' are joined by the conductor 44. By 50 tracing the circuit from grounded conductor 38 through contact s⁶, armatures s⁵, conductor 44, contact t', armature t, wire 43, resistance s to battery X⁵ and ground it will be seen that while the ringing trip relay T 55 is deenergized ringing current will be transmitted to signal the called party's line because a short circuit exists to render the cut through relay S inoperative. When the called party answers the relay T is energized 60 by lowering the line resistance and the attraction of the armature t opens the short circuit and permits the relay S to operate to attract its series of armatures. The pulling up of the armatures s' and s² connects the conductor 39 and 40, leading from the switch

wipers, to forward contacts s⁷ and s⁸ from which lead conductors 45 and 46 to armatures u and u' on the called party's answering relay U. The forward contacts of these armatures are terminals for the calling line A, 70 B. The relay U is provided with two windings u² and u³ each of which is connected at one end to the conductors 45 and 46 and at their opposite extremities to the two poles of the battery X⁶. Consequently these armatures are attracted simultaneously with the armatures of the cut through relay S and the calling party's line is extended through the switch wipers to the called line. Upon the called party answering his line is closed at 75 the switch hook contacts H² and the current which then flows over it from battery X⁶ holds the armatures u, u' and s', s² closed to permit conversation to be carried on between the two telephone stations. 80

If the called party's line is in use the switch wiper 3^a comes to rest on a busy or grounded terminal with the result that a circuit is established through the battery X³, the winding p' and the armature 32 90 before the latter is released from the position in which it was attracted when the winding p is energized by the closing of the test contacts m⁸ upon each step of the motor magnet. The retaining of the busy test 95 magnet energized by the ground picked up by switch wiper 3^a opens the circuit of the ringing relay Q by holding the armature q attracted. The busy test relay P under these 100 circumstances applies a busy tone to the calling party's line from a specially designed commutator V in an induction circuit, which is closed by the armature v on relay P to dispatch the busy signal over a conductor 49 to the calling subscriber's line. 105

The main control relay A' and its associate relay C may be similarly constructed so far as their electrical constants and mechanical features are concerned it being only necessary in practice to adjust the relative spring tension of their respective sets of contacts as above described. The control relay arrangement and associated switch circuits will function satisfactorily with the present day type of dialing devices and my arrangement of the main and associate control relays lend themselves to various circuit adaptations as shown in Figs. 4 and 5 will be seen from the illustration. In Fig. 4 I have shown the main control relay A 11 and its associate control relay C 10 as provided with double windings employed for line balancing purposes. 115

Fig. 5 is submitted as an illustration of the manner in which the main and associate control relays A 11 and C 100 may be incorporated in a single relay structure. Here the windings are included in the two sides of the subscriber's line and arranged upon a common core. Opposite the end of the core 120 125 130

which serves as an associate control relay I provide the impulse contacts C 200 controlling the motor magnet circuit.

In this illustration I have also shown 5 schematically another way for arranging the main control relay contacts so that it is immaterial whether or not the controlling armature flutters. In this case the armature of the main control relay A 110 is indicated by 10 e carrying at its lower end a pin g which at its free end abuts a switch lever h. Armature e is retracted by a spring e' and the lever h is moved forwardly by the action of a separate spring h' into engagement with a 15 forward grounded contact i. These two elements serving the function described for the main control relay contacts a². The free end of pin g in its retracted position engages the face of the switch lever h and as the spring 20 h' is of less tension than that of spring e' the latter will normally cause said lever to move out of engagement with the contact i. The distance through which the armature e is moved is sufficiently greater than the distance 25 between lever h and its contact i so that a considerable movement is permitted the armature e if it tends to flutter without causing pin g to cause the disengagement of the contacts h and i.

30 What I claim is:

1. In a telephone system, the combination with a switch mechanism comprising a motor magnet for advancing it and a locking magnet for holding it in its adjusted position, a 35 pair of subscriber's line conductors, means for transmitting current impulses thereover, of main and associate control relays in said conductors, each having sets of contacts positioned to operate in reverse directions when 40 said relays are energized, one of said sets of contacts being given a normal spring tension and the other a relatively weak spring tension and a slow to release relay arranged to be energized upon the attraction of the weak set 45 of contacts, a source of current for said line and for operating said magnets, an energizing circuit for the locking magnet closed by said slow relay, and a circuit for the motor magnet controlled by the normally adjusted 50 contacts on the other line relay and intermittently energized in response to current interruptions on the telephone line.

2. In a telephone system, the combination with a pair of subscriber's line conductors 55 each having a control relay provided with contacts, said relays being simultaneously energized when said line is closed and operating to open and close their respective pairs of contacts, one of said pairs of contacts having a given normal adjustment and the other a relatively weak spring tension and a slow 60 to release relay controlled by the latter set of contacts, of a switch mechanism comprising a locking magnet and a motor magnet, a circuit for the former controlled by the slow

relay and maintained energized while the telephone line is closed, a circuit for the motor magnet arranged to receive current impulses upon the vibration of the normally adjusted pair of contacts, a source of current 70 for said telephone line and for operating said magnets and an impulse device on the telephone line for intermittently transmitting current impulses to actuate said motor magnet. 75

3. An automatic telephone system comprising a pair of line conductors leading from a subscriber's substation apparatus consisting of an impulse device and a telephone apparatus having switch hook contacts, a pair of relays in said conductors simultaneously energized upon closure of the telephone circuit each having a pair of contacts one of which is given a normal adjustment to vibrate positively in unison with the current interruptions 80 created by the impulse device and the other pair given a relatively weak adjustment tending to cause them to hold over during such interruptions, a slow to release relay controlled by the last mentioned contacts, a step-by-step switch mechanism comprising a slow to release locking magnet and a motor magnet, a circuit for the former closed by the slow relay and a circuit for the motor magnet arranged to receive current impulses to 85 advance the switch upon each movement of the normally adjusted contacts, and a source of current for operating said line and said magnets. 90

4. An automatic telephone system comprising a pair of subscriber's line conductors having a subscriber's sub-station telephone apparatus, and an impulse device, main and associate control relays in said conductors, the main relay having a pair of normally open weakly adjusted pair of contacts and the associate relay having a normally closed pair of contacts having a spring tension sufficient to positively respond in unison with current interruptions created by the impulse device, a switch mechanism embodying a slow to release locking magnet and a motor magnet for advancing the switch step-by-step, a circuit for the locking magnet controlled by said slow relay and a circuit for the motor magnet controlled by the contacts on the associate relay. 110

5. An automatic telephone system consisting of a subscriber's telephone apparatus, an impulse transmitter and a pair of line conductors, similar relays in the two sides of the line each having a pair of contacts and a source of battery current for said line, a main relay on the battery or wet side of the line having contacts which are normally open and adjusted with a weak spring tension and a relay on the grounded or dry side of the line having contacts which are normally closed and adjusted with a sufficient spring tension to positively respond in unison with the cur- 120 125 130

- rent interruptions created by the impulse device, a step-by-step switch having a motor magnet for advancing it provided with a circuit controlled by the normally closed pair of contacts, a slow to release relay energized by the closing of the normally open pair of contacts, a magnet for locking the switch in its adjusted position having a circuit controlled by said slow relay.
- 10 6. An automatic telephone system consisting of a subscriber's telephone apparatus, an impulse device and a pair of line conductors, a source of battery current for said line, a main relay in the battery side of the line having a pair of normally open contacts, an associate relay in the dry side of the line having a pair of normally closed contacts, a slow to release relay energized simultaneously with the main relay and operating to condition a circuit through the contacts of the associate relay, a switch having a motor magnet provided with a circuit leading through the associate relay contacts and adapted to be energized in unison with current interruptions created by the impulse device to advance the switch, a locking magnet for holding the switch in its adjusted position having a circuit controlled by said slow relay and a source of current for operating said magnets.
- 25 7. An automatic telephone system consisting of a subscriber's telephone apparatus, an impulse transmitter and a pair of line conductors, a source of battery current for said line, a main relay in the battery side of the line having a pair of normally open spring contacts having a relatively weak adjustment, an associate relay in the dry side of the line having a pair of normally open spring contacts adjusted to positively close in unison with current interruptions created by the impulse device, a slow to release relay energized simultaneously with the main relay, contacts on the slow relay which are closed when it is energized to condition a circuit for the associate relay contacts when they are closed, a switch having a motor magnet provided with a circuit leading through the associate relay contacts and adapted to be energized upon their release to advance the switch, a locking magnet for holding the switch in its adjusted position and a circuit therefor maintained through the slow relay contacts.

In testimony whereof, I have signed this specification.

CHARLES L. GOODRUM.
